UNITED STATES PATENT OFFICE.

BENJAMIN COLE, OF BROOKLYN, NEW YORK.

PENHOLDER.

Specification of Letters Patent No. 22,938, dated February 15, 1859.

To all whom it may concern:

Be it known that I, BENJAMIN COLE, of Brooklyn, county of Kings, and State of New York, have invented a new and Improved Mode of Constructing Penholders; and I do hereby declare that the following is a full and exact description thereof, reference being had to the accompanying drawings and to the letters of reference marked 10 thereon.

The nature of my invention consists in constructing a penholder (A) of a tubular form—the end holding the pen to be composed of three or more elastic shanks or 15 fingers (b) so arranged that two of the fingers will grasp the pen upon the sides or edges, and the remaining finger or fingers will press upon the back part of the pen and force it against and under the small shoulders (c) on the edges of the lateral fingers; 20 thus securely holding the pen in its place.

The pen is prevented from passing too far

up into the holder by a piece of metal (a), (turned down from a cut in the back of the holder), which acts as a stop.

The pen is designed not to be inserted in the holder in the ordinary manner from the end, but to be pressed flat-wise on the elastic fingers.

What I claim as my invention, and desire to secure by Letters Patent, is—

The construction of a penholder with three or more elastic shanks or fingers (b) so arranged that the spring of said fingers will hold the pen, by pressing it against and under the shoulders (c) of two lateral fingers, and thus admit the introduction of, and be adapted to pens of any ordinary size or thickness.

BENJAMIN COLE.
